UNITED STATES PATENT OFFICE.

WILLIAM F. LUDWICK, OF BEAUMONT, KANSAS, ASSIGNOR OF ONE-HALF TO CHARLES G. MILLER, OF ENID, OKLAHOMA.

NUT-LOCK.

1,078,738.

Specification of Letters Patent. Patented Nov. 18, 1913.

Application filed January 4, 1913. Serial No. 740,243.

To all whom it may concern:

Be it known that I, WILLIAM F. LUDWICK, a citizen of the United States, residing at Beaumont, in the county of Butler and State 5 of Kansas, have invented a new and useful Nut-Lock, of which the following is a specification.

This invention aims to provide a nut lock which may be fashioned at trifling cost from 10 inexpensive material, the construction of the device being such that the same may be employed without injuring the material in which the bolt and nut structure is mounted, an adjustment of the nut, and a firm securing 15 of the nut against rotation being possible.

The invention is shown in a single perspective figure.

The nut lock herein disclosed comprises 20 a resilient plate 32 having angularly disposed, projecting, supporting flanges 34 at its ends and provided in its side edges with slits defining a reduced neck 35, there being locking tongues 37 upstanding from the 25 plate 32 at the ends of the slits, the plate 32 having a bolt receiving opening 36 located in the neck 35 and between the tongues 37, the plate 32 being continuous along its longitudinal center, saving for the bolt receiving 30 opening 36.

The reduced neck 35 formed intermediate

the ends of the plate 32 gives the plate sufficient resiliency to exercise its functions. The tongues 37, as will be understood readily, constitute elements which hold the nut 35 against rotation. It is to be observed that the plate 32 is continuous along its longitudinal center, saving for the bolt receiving opening 36. The plate, therefore, although resiliency, is rendered stiff enough to hold 40 the tongues engaged with the nut.

Having thus described the invention, what is claimed is:—

A nut lock comprising a plate having angularly disposed, projecting, supporting 45 flanges at its ends and provided in its side edges with slits defining a reduced neck, there being a locking tongue upstanding from the plate at one end of each slit, the plate having a bolt receiving opening 50 located in the neck and between the tongues, the plate being continuous along its longitudinal center, saving for the bolt receiving opening.

In testimony that I claim the foregoing 55 as my own, I have hereto affixed my signature in the presence of two witnesses.

WILLIAM F. LUDWICK.
